UNITED STATES PATENT OFFICE

JOHN KOVATS, OF BRIDGEPORT, CONNECTICUT, ASSIGNOR TO THE LEG-O-MATIC COMPANY, OF BRIDGEPORT, CONNECTICUT, A CORPORATION OF CONNECTICUT

FOLDING TABLE

Application filed May 31, 1930. Serial No. 458,011.

This invention relates to a table, particularly to a means for mounting the supporting legs of the table, and has for an object to provide means for so connecting the supporting legs to the table that they may all be folded against the under side of the table, and are connected by mechanism so that the swinging of any leg to or from the extended or supporting position will impart a similar 10 and simultaneous movement to each of the other legs.

It is also an object of this invention to provide a construction in which there is an individual collapsible bracing or locking 15 means for each leg, which is so connected with the bracing means of each of the other legs that they will all automatically brace and lock the legs when said legs are swung to the supporting position, and the collapse of any one bracing means will unlock and collapse all the other bracing means to permit the legs to be swung to folded position.

It is a further object of this invention to provide a bracing means that can be collapsed 20 only by proper pressure against any one of the interconnected bracing means and that will resist collapse by pressure against any of the supporting legs so that although all the legs may be swung to extended position by 25 swinging any individual leg on its pivot, the legs may be swung to folded position only after any one of the bracing means has been properly partially collapsed; and the legs are rigidly held in the supporting position to 30 provide a rigid support for the table.

It is still an additional object of this invention to provide a bracket and leg pivoting holder of such construction that the leg need not be additionally braced to prevent 35 it from collapsing in the wrong direction.

It is still another object of this invention to provide a construction of this character in which practically the entire structure may be stamped from sheet metal and may be 40 manufactured and assembled at relatively low cost.

With the foregoing and other objects in view, the invention consists in certain novel features of construction, combinations and arrangements of parts as will be more fully

disclosed in connection with the accompanying drawing, in which:

Fig. 1 is a bottom plan view of a table showing the legs folded against the under side thereof and partially broken away to 55 show details of the construction.

Fig. 2 is an enlarged view of one corner of the underside of the table with the leg in extended or supporting position.

Fig. 3 is a section looking in the direction 60 of the arrows on line 3-3 of Fig. 2.

Fig. 4 is a detail section of the rack clamped to the cable on line 4-4 of Fig. 3.

Fig. 5 is a detail section of the rack slidably affixed to the table on line 5-5 of Fig. 3. 65

Fig. 6 is a plan view of a bracket which is affixed to each inner corner of the table and serves as a means for pivotally affixing the leg and the hinged brace to the table in proper position. 70

Fig. 7 is a plan view of this same bracket at right angles to the view shown in Fig. 6.

Fig. 8 is a front plan view of the leg pivoting holder.

Fig. 9 is a side plan view of the holder 75 shown in Fig. 8.

This device is adapted for tables of various types but is especially intended for use on what are commonly known as card tables in which the legs are foldable against the under side of the table top, so that the table may be folded into a small space and put away into a closet or other suitable space when not in use, and the device is, therefore, shown in the drawing as applied to this type 80 of table. The table top is shown at 12 which, of course, may be of any suitable material and may be finished on the top or covered with any suitable cover as is found desirable. Secured to the under side of this top of the table and extending about the periphery thereof are usually mounted wooden bars 13 which 85 strengthen and stiffen the table top and assist in preventing warping. The table shown is a substantially square or rectangular table 90 and is, therefore, provided with a supporting leg 14 at each corner. These legs are each pivoted to the table so as to fold or swing against the under side thereof and they are 95 all mounted in the same manner. They thus, 100

each swing in the same direction in relation to the periphery of the table from their individual corners and lie substantially parallel with the bar or flange 13 when they are folded 5 against the under side of the table top. As the means for mounting each is the same as that for mounting each of the other legs one set of dies may be used for making all the mountings and they are, therefore, each interchangeable, and I will describe but one of them.

The legs are substantially rectangular in cross section but, of course, may be of any shape desired. The upper end of each leg 15 is secured in a holder 15 which is made of sheet metal and is substantially U-shaped in cross section to receive the upper end of the leg and therefore, embraces it on three sides, and it is preferably secured thereto by a bolt 20 or screw 16. Projecting from the end of the leg this holder is provided with a narrow flange 17 and a wide flange 18 which form continuations of the opposite side walls of the holder; projecting from flanges 17 and 18 25 are the ears 19, and the leg is mounted by pivoting ears 19 in a bracket 20 which is affixed in each corner by any suitable means on the under side of the table. This bracket 20 is also made of metal of suitable gauge and 30 has a base portion 21 which abuts against the under side of the table 12. A short flange 22 depends from portion 21 at a distance from the corner equal to the width of holder 15, while a long flange 23 depends from portion 35 21 and abuts along bar 13 for a substantial distance providing a means for affixing certain later described elements to the table. Pivot openings 24 are provided in flanges 22 and 23 for pivoting ears 19 of the leg holder 40 15, whereby the legs 14 may be extended into supporting position or folded in close position about the pivots 25. Due to the width of flange 18 on the holder, the leg is well supported so there is but little danger of the leg 45 14 collapsing in the wrong direction, and hence, no additional brace is necessary.

Mounted on each bracket 20 on a suitable stud 26 in the opening 27 is a grooved pulley 28. There is, therefore, one of these pulleys 50 28 at each corner of the table, and there is a flexible member 29 which runs over these pulleys or rollers. This flexible member is preferably in the form of a wire cable as that has been found to be very satisfactory, 55 and the free ends of this cable are connected by suitable connecting means as a turnbuckle so that when mounted the cable is a substantially continuous element. This turnbuckle for the ends of the cable, as shown 60 in the drawing, comprises an internally threaded member 30 connected to one end of the cable and another internally but oppositely threaded member 31, connected to the other end of the cable. A turn screw 32 having its ends oppositely threaded to corre-

spond to the threads in members 30 and 31 connects these members and may be manipulated to adjust the tension on the cable and make it as tight as is found satisfactory. For best operation the tension on the cable 70 should be sufficient to keep it taut.

Adjacent each corner of the table there is a clamp 33 secured to the cable. The clamp shown in the drawing comprises a clamping element 34 screwed as at 35 to a long rack 36 which is slidably affixed to the table by a pair of guides 37 for reciprocatory movement. Between the guides 37 are teeth 38 on rack 36, and it is apparent that movement of the cable in either direction will correspondingly move each rack 36.

A hinged brace 39 is pivoted to each leg at 40 and is pivotally affixed to the table by means of the pivot 41 in the opening 42 on flange 23. The brace 39 has a lip 43 preventing it from opening materially beyond a straight angle as shown in Fig. 3 but allowing the brace to be collapsed to closed position, thereby folding legs 14 to the position shown in Fig. 1. That end of the brace which is pivoted to the table has a geared segment 44 formed about the pivot 41, and this geared segment 44 is in constant mesh with rack 36 so that movement of the rack in either direction will cause rotation of the geared segment 44, and, vice versa, rotation of the segment 44 will cause movement of the rack.

In describing the operation it will be assumed that the legs are folded against the bottom of the table, as shown in Fig. 1. If now, the operator swings any one of the legs 14 about its pivot to a position at right angles to the table top or that is, to the extended or supporting position, this action will open the hinged brace and pivotally rotate the geared segment 44 thereof and move the rack 36. The movement of the rack moves the cable 29, and cable 29 simultaneously moves each of the other racks 36, rotating each corresponding gear 44 to open each corresponding hinge 39 and thus, simultaneously to open each leg 14 to the supporting position. As the legs reach the supporting position, the hinge 39 opens to a straight angle against lip 43, thereby bracing or locking each leg against collapse. It is obvious that any pressure against the leg will not act to open the hinge while it is in such a straight angle, for the force of such pressure would act in time with the center of the hinge pivot and have no opening effect thereon, and hence each leg is automatically braced or locked in this extended or supporting position. If the lip 43 is so located as to permit center of pivot 39' to pass beyond the line joining the centers of pivots 40 and 41 then the greater the pressure tending to collapse the legs the greater the locking effect.

It will be seen that the hinged brace 39 braces the leg in one direction or plane while 130

the wide flange 18 on the holder 15 serves to brace the leg in a direction or plane at right angles thereto, and therefore, the leg when in the upright or supporting position is braced in all directions giving a very rigid construction and preventing wobbling of the table.

To collapse the legs or fold them against the under side of the table all that is necessary is for the operator to press downwardly against the back of any brace 39 on the side opposite from lip 43, thereby partially collapsing or unlocking the brace. This action partially collapses and unlocks the particular leg involved, and at the same time moves the rack and hence the cable to move all the other racks and such movement of each rack serves to simultaneously partially collapse and unlock each corresponding hinged brace 39. Now all the operator has to do is to merely swing inwardly any one of the legs, usually the leg he has just unlocked, and the cable will simultaneously swing all the other legs to the folded position. It will, therefore, be seen that with this construction the legs may all be simultaneously swung to the extended or supporting position and be automatically braced or locked therein by the swinging of any one of the legs to this position. Also that the act or unlocking any leg will simultaneously unlock all the other legs and they all are swung simultaneously to the folded position by the single act of swinging one of the legs to this position. It will be noted also that practically all the parts can be made of sheet metal, and that this construction is a very simple one which may be manufactured and assembled at a relatively low cost.

Having thus set forth the nature of the invention, what is claimed is:

1. In a table, a plurality of supporting legs pivoted to the table on individual pivots and each capable of folding against the under side of the table, a movable connecting means carried by the table, and a hinged connection between the said connecting means and each of the legs, said hinged connection comprising a pair of links pivotally connected at their ends, one of said links of each connection having its free end pivoted to a leg and the other having its free end pivotated to the connecting means, said connection adapted to have the pivotally connected ends of their links pressed downwardly whereby said connections are capable of transmitting movement from any leg to each of the other legs to extend the legs to supporting position and to fold them against the table as the hinged means is straightened and collapsed.

2. In a table, a plurality of supporting legs pivoted to the table so as to fold against it, guide means secured to said table, a continuous connected member movably retained by said guides means, a hinged brace pivoted on

each leg, and, a toothed means gearing the brace to the connected member.

3. In a table, a plurality of supporting legs pivoted to the table so as to fold against it, guide means secured to said table, a continuous connected member movably retained by said guide means, a rack clamped to said connected member at each leg, and a hinged brace pivoted to each leg and geared to each rack clamp. 70

4. In a table, a plurality of supporting legs pivoted to the table so as to fold against it, a continuous connected member movably secured to the table, a hinged brace pivoted to each leg, and a toothed means gearing the 80 brace to said connected member.

5. In a table, a plurality of supporting legs pivoted to the table so as to fold against it, a roller guide secured to the table adjacent each leg, a flexible cable passing over said 85 guide, a hinged brace pivoted to each leg, and a toothed means gearing the brace to the table.

6. In a table, a plurality of supporting legs pivoted to the table on individual pivots arranged so that all the legs fold in the same direction with respect to the periphery of the table, and connections including toothed means between each adjacent pair of the legs for transmitting similar movement from any leg to each of the other legs to extend the legs to supporting position or fold them 90 against the table. 95

7. In a table, a plurality of supporting legs pivoted to the table and foldable against 100 it, and hinged and toothed gear means between each adjacent pair of legs and connecting all the legs so that operation of any leg on its pivot will impart similar movement to all the other legs. 105

8. In a table, a plurality of supporting legs pivoted to the table and foldable against it, means for connecting the legs with each other so that movement of any leg will give similar movement to the other legs, hinged means 110 for bracing each leg in supporting position, and toothed means gearing the hinged means to the connecting means whereby on the collapse of any one hinged means the same functions to operate said connecting means to move the same to collapse the other bracing means. 115

9. In a table, a plurality of supporting legs pivoted to the table so as to fold against it, guides secured to the table, a continuous flexible member passing over said guides and hinged toothed gear connections from said member to the respective legs to swing them on their pivots by movement of said member. 120

10. In a table, a plurality of supporting legs pivoted to the table so as to fold against it, guides secured to the table, a continuous flexible member passing over said guides, a rack clamped to said flexible member, and a 125 geared hinge in mesh with said rack and piv- 130

oted to each leg to brace said leg when said hinge is straight and to fold said leg when movement of said flexible member collapses said hinge.

- 5 11. In a table, a plurality of supporting legs pivoted to the table so as to fold against it, a roller guide secured to the table adjacent each leg, a continuous flexible cable passing over the guides, a hinged brace pivoted to each leg and having a geared segment pivoted to the table adjacent each leg, and racks clamped to the cable in constant mesh with each brace, whereby the hinging or unhinging of any one brace imparts a like motion to every other brace to fold or unfold the legs.
- 10 12. In a table, a plurality of supporting legs pivoted to the table so as to fold against it, guides secured to the table, a continuous flexible member passing over said guides, a rack clamped to said flexible member adjacent each leg and slidably affixed to the table, a hinged brace connected to each leg, said hinged brace comprising two sections hinging only to substantially a straight angle in
- 15 one direction, one of said sections being pivoted to a leg and the other of said sections being pivotally affixed to the table, a gear segment formed on said last named section about its pivot to the table, said gear segment being in constant mesh with said rack.
- 20 13. In a table, a supporting leg pivoted thereto adjacent each corner and adapted to fold against the table, a guide mounted adjacent each leg, a flexible cable passing over said guides, a brace for each leg pivoted to said leg and pivotally affixed to the table inwardly of the pivotal mounting for said leg, said brace being hinged and collapsible to pivot the leg to folded position, a gear segment formed on said brace about its pivot to the table, a rack in constant mesh with said gear segment slidably affixed to the table, said rack being clamped to and movable with said flexible cable.
- 25 14. In a table, a plurality of supporting legs pivoted to the table so as to be foldable against it, a guide secured to the table adjacent each leg, a flexible cable passing over the guides, a rack secured to the cable adjacent each leg, means for slidably affixing said rack to the table, and geared means meshed with the rack connecting with the adjacent leg capable of swinging the leg on its pivot by movement of the cable.
- 30 15. In testimony whereof I affix my signature.
JOHN KOVATS.
